UNITED STATES PATENT OFFICE

2,157,802

DOUCHE NOZZLE

Frank Rissinger, Columbia, Pa.

Application July 21, 1937, Serial No. 154,867

1 Claim. (Cl. 128—245)

This invention relates to a douche nozzle, the general object of the invention being to provide the nozzle with an elongated part of trough shape for entering the vagina and a vertically arranged part having a chamber therein opening out through its front face for covering the external part so that when fluid is introduced into the nozzle both the external and internal parts will be contacted by the fluid.

10 This invention also consists in certain other features of construction and in the combination and arrangement of several parts, to be herein-after fully described, illustrated in the accompanying drawing and specifically pointed out in 15 the appended claim.

In describing the invention in detail, reference will be had to the accompanying drawing wherein like characters denote like or corresponding parts throughout the several views, and in which:

20 Figure 1 is an elevation with parts broken away, of the invention.

Figure 2 is a top plan view.

Figure 3 is a view looking toward the front of the device.

25 As shown in these views the device A is formed of one piece of material and may be formed of any suitable material and it comprises the elongated part 1 and the vertical part 2, the part 1 tapering from the part 2 to its free end and 30 being of trough shape with the sides of its free end rounded as shown at 3. The part 2 is formed with a chamber 4 which opens out through the front face of the part 2 and the chamber forms a continuation of the channel of part 1, the sides 35 and top of the chamber being closed so that the edges of the part 2 can be pressed against the exterior part of the female organ when the part 1 has been placed in the vagina.

35 A tube 5 is connected with the lower part of the member 2 and is intended to receive one end of a hose which is to be connected to a source of supply of medicinal fluid or the like.

Thus it will be seen that when the device is placed in position and the fluid permitted to flow into the device said fluid will pass along the trough part 1 and thus coming into contact with the internal walls of the passage and some of the fluid will enter the chamber 4 of the part 2 and contacts the external part.

It is thought from the foregoing description that the advantages and novel features of the invention will be readily apparent.

10 It is to be understood that changes may be made in the construction and in the combination and arrangement of the several parts, provided that such changes fall within the scope of the appended claim.

15 Having described the invention what is claimed as new is:

A douche nozzle for treating internal and external parts of a vagina in a body, said nozzle comprising a member formed of a single piece 20 of material and having an elongated trough-shaped part for entering the vagina, said part tapering from its outer end to its inner end and said part including bottom and side walls with its top open and its inner end open and said bottom and side walls being imperforate, the outer end of said trough-shaped part being enlarged, and a chamber forming part extending outwardly and upwardly from the enlarged outer end of the trough-shaped part adapted to fit the body, the 25 chamber in said chamber part being entirely closed except at that side which faces the trough-shaped part with the lower part of the chamber forming a continuation of the trough formed by the trough-shaped part and a tube in communication with the lower end of the chamber for introducing liquid into the trough formed by the trough-shaped part and into the chamber of the 30 chamber part.

FRANK RISSINGER.
